JOURNAL BOX CLOSURE

William L. Dwyer, Indianapolis, Ind., assignor to
 Railway Service and Supply Corporation, Indianapolis, Ind., a corporation of Indiana

Application June 27, 1946, Serial No. 679,818

3 Claims. (Cl. 308—51)

1

This invention relates to journal boxes for railway axles, and particularly to an improved closure means therefor.

The conventional journal box lid is a relatively heavy, substantially rectangular piece of metal, hinged at the top to a suitable lug or boss cast integrally with the box. It is generally equipped with a spring which reacts between the hinge point and the lid to keep the latter in its closed position. This old and rather well known construction is subject to a number of disadvantages. Perfectly tight closure of the box opening is hard to obtain due to the fact that the position of the lid is always controlled to a greater or less extent by its hinge joint, so that unless the bearing surface around the opening in the box is accurately adapted or machined to cooperate exactly with the hinge and the lid, the latter may not come into actual uniform contact with all parts of the bearing surface around the opening so that small cracks or crevices are left, through which dirt can enter the box. In addition, this old type of relatively heavy lid with its spring construction has been subject to damage by virtue of the fact that after opening of the lid and inspection of the box, the lid is generally pushed suddenly in the direction of its closed position after which it slams shut with considerable force and the development of a great deal of noise. Furthermore, the vibration or flutter encountered in operation tends to destroy the alignment between the lid and the box as a result of wear in the hinge, including the boss or lug which is an integral part of the box. This condition cannot be rectified without either replacing the whole journal box or building up a new boss, either of which is relatively expensive. The same operating conditions cause considerable damage to the engaging faces of the lid and the journal box, with a resulting breakdown in the effectiveness of the sealing properties of the cover. To the extent that this is occasioned by damage to the journal box, the remedy is again either a complete replacement of the box or an expensive building up and machining of the surface. Inasmuch as many journal boxes are cast integrally with the side frames of the car trucks, in many cases damage to the box may mean that the whole side frame must be replaced.

An object of the invention is to provide a journal box closure assembly including lid, spring, hinge, and latch means which can be mounted on any journal box regardless of the condition of the hinge boss or the face of the journal box opening, the assembly being readily secured to

2

or detached from the journal box, whereby in one operation all of the elements of the journal box closure subject to damage or wear are replaceable as a unit.

A further object is a journal box closure assembly providing pivotal mounting for a sealing lid at the side of the journal box opening, the assembly being further adapted to provide alternatively hinge mounting for the sealing lid at either side without change in the design of the assembly.

Another object of my invention is a reduction in the amount of flutter, through the employment of a journal box lid of relatively light weight.

15 A still further object of the invention is to provide a means for securing the lid in position by means of a positively operating latch.

The invention also contemplates a journal box closure which provides perfect alignment between the lid and the surface engaged by the lid, thereby insuring a perfect seal for the retention of lubricant and the exclusion of dust, dirt, moisture, and the like.

20 How the foregoing and other advantages are attained is illustrated in the accompanying drawings in which:

Figure 1 is a side view, partly in elevation and partly in section, of my improved journal box closure, and including a fragmentary showing of the journal box on which the closure is mounted;

Figure 2 is a front elevation of the closure taken along the line 2—2;

Figure 3 is a sectional view, taken along the line 3—3 of Figure 2;

30 Figure 4 is an elevational view taken along the line 4—4 of Figure 2, and showing my novel hinge;

Figure 5 is a sectional view along the line 5—5 of Figure 3; and

40 Figure 6 is a perspective view of my novel face frame.

According to the invention, the journal box closure assembly comprises three principal parts: the face frame 1, the hinge arm 2, and the lid 3.

45 The face frame may conveniently be formed of sheet material; for example, by stamping. From Figure 6 it will be seen that the frame is provided with a number of lugs 4, disposed conveniently at the four sides of the frame. These lugs are displaced from the plane of the frame proper to a degree sufficient to bring them into contact with the journal box 5. Although any convenient number and arrangement of the lugs may be employed, the form of invention illustrated in the drawings employs two on each of

the four sides of the frame. When the frame is installed on the journal box, it is placed in position over the opening, with the lugs in contact with the box, and secured in that position, for example by welding or brazing the lugs to the box, as at 6, 7, 8 and 9.

It will be noted that the original hinge boss 5a has no function in connection with my novel journal box assembly.

The frame is provided, at one side, with hinge loops 10, and at the other with a latch retainer 11. As seen in Figure 2, hinge arm 2 engages at one end with the hinge loops, the hinge arm being provided with loops 13, and the arm being secured to the frame by means of hinge pin 14, which passes through both the loops 10 and the loops 13.

At its opposite end, the hinge arm is provided with a latch 15 pivoted on the hinge arm by pin 16, the latch being adapted to engage with latch retainer 11.

The lid 3, as may be seen in Figure 2, is substantially rectangular, its dimensions being appropriate for covering the opening of the journal box to which it is applied. As will be seen in Figure 3 the lid is provided with a depressed central portion 17 which projects into the opening of the journal box.

Two channel members 18 are secured to the outer surface of the depressed portion of the lid by rivets 19 or other suitable fastening means. The channel members are adapted to receive the ends of the lid loading spring 20 which are slidably retained in the channels by pins 21.

The center of the lid loading spring 20 is secured to hinge arm 2 by means of spring retaining clip 22 and bolts 23.

As will be seen from Figure 3, the lid is maintained in position only through the intermediation of the lid loading spring and does not come into direct contact with the hinge arm.

Referring further to Figures 1 and 3, oil resisting gaskets 24 and 25 are located respectively between the engaging faces of the journal box opening and frame 1, and between frame 1 and lid 3. Gasket 24 is secured to frame 1, while gasket 25 may be secured to either the frame or the lid. Preferably, gasket 24 should be detachably secured to the frame in order that it may be replaced when necessary. Gasket 25 should be detachably secured to either the frame or lid in a manner to insure its remaining in position during the opening and closing of the lid, and yet being removable for replacement when necessary.

In order to close the journal box, the hinge arm and lid are swung to the closed position, pressure is exerted on the latch end of the hinge arm compressing the spring, and the latch is moved to engagement with the latch retainer. To open the box, the latch is pulled from engagement with the latch retainer by means of the latch loop 26, and the hinge arm and lid are swung to the open position. As is well known, the opening in the conventional journal box is in a plane inclined upwardly and inwardly from the vertical. The provision of a side hinge mounted in the plane of the journal box opening permits the lid to remain either in the fully opened position or in the substantially closed position through the operation of gravity.

From the foregoing, it will be seen that my invention provides a simple and effective closure means for journal boxes.

One of the advantages of the invention lies in

the fact that the whole assembly may be mounted on the journal box at the car, thus eliminating the necessity for removing the car to the shop. All that is necessary for installation is to remove the original lid, place my novel closure assembly in position over the opening in the box, and secure it in that position by welding the tabs on the face frame to the journal box.

Another advantage of the invention is inherent in the fact that the face frame, hinge arm, and lid are symmetrical in a vertical sense. This permits the assembly to be mounted on the journal box with the hinge at whichever side is preferable or desirable in the individual case to avoid obstructions which may prevent opening of the lid to one side or the other.

A further advantage of the invention is the complete elimination of the condition of the cast hinge boss on the journal box as a factor in the effectiveness of the seal, which advantage arises out of my provision of a separate hinge as a part of my journal box closure assembly.

The combination of a separate hinge, positive latch mechanism, light weight lid, and spring loading for the lid is effective in reducing to a large extent the destructive flutter caused by the vibration encountered under operating conditions, which is responsible for a large portion of the wear and damage to conventional journal box closures.

Similarly, the arrangement of latch and spring employed in the invention considerably reduces the damage which is ordinarily occasioned by the slamming of the lid under the pressure of the spring after inspection of the lubricating chamber.

An outstanding advantage lies in the clear, unobstructed view of the interior of the box when the lid is in its open position, for inspection of wedge, bearing, journal and packing.

Finally, the inclusion in a readily replaceable assembly of all parts of the journal box closure which are subject to wear or damage in operation completely eliminates the wasteful necessity of either complete rejection of side frames or journal boxes or expensive machining of journal box opening faces and/or hinge bosses which are occasioned by wear or damage in the conventional journal box closure arrangement in which the surfaces which are subject to wear and damage are integrally cast with the journal box.

I claim:

1. As an article of manufacture, a replaceable face frame for journal box openings, comprising a plane portion adapted to frame the opening of a journal box, a plurality of tab portions projecting outwardly from the journal box face of the plane portion and adapted to be bent into contact with the walls of the journal box, and a lid-supporting hinge portion projecting outwardly from the opposite face of the plane portion and adapted to support a journal box lid with freedom for swing motion into and from a position of sealing engagement with the plane portion of the frame.

2. Construction in accordance with claim 1 and further having a latch portion formed integrally with the frame to cooperate in maintaining a journal box lid in sealing engagement with the frame.

3. A closure assembly for the opening of a journal box, comprising a face frame adapted to seat against the rim of the opening, lugs projecting from the frame and adapted to be bent so as to

embrace the box structure around said opening, a hinge lug on one side and a latch lug on the opposite side, a hinge member pivoted for swinging motion on said hinge lug, a closure plate proper carried by said hinge member, and latch means for securing the hinge member to said latch lug, the face frame being of symmetrical construction whereby the hinge member can be swung from either side of the box opening.

WILLIAM L. DWYER.
